UNITED STATES PATENT OFFICE.

EARNEST LOHSAND, OF CHICAGO, ILLINOIS.

VEHICLE.

SPECIFICATION forming part of Letters Patent No. 737,852, dated September 1, 1903.

Application filed September 22, 1902. Serial No. 124,399. (No model.)

To all whom it may concern:

Be it known that I, EARNEST LOHSAND, a citizen of the United States, residing at Chicago, in the county of Cook and State of Illinois, have invented a new and useful Improvement 5 in Vehicles, of which the following is a specification.

My invention relates particularly to road-going vehicles; and my primary object is to provide an automobile of improved general construction, though, as will be understood from the following description, the invention is applicable to horse-drawn vehicles.

The invention is illustrated in its preferred embodiment in the accompanying drawings, in which—

Figure 1 represents a side elevational view of an automobile embodying my invention, certain parts being removed; Fig. 2, a plan 20 sectional view looking down upon the running-gears of the vehicle; Fig. 3, a vertical sectional view taken as indicated at line 3 of Fig. 2; Fig. 4, an enlarged broken vertical section taken as indicated at line 4 of Fig. 2, 25 and Fig. 5 a broken view taken as indicated at line 5 of Fig. 4.

The preferred construction is as follows:

A A', B B', and C C' represent the sets of wheels of the vehicle; D D' D'', the axles of 30 the vehicle; E, a sprocket-wheel through which power is applied to the shaft D'; F, sprocket wheel and chain connections between the shaft D' and the shaft D; G, similar connections between D' and the shaft D''; 35 H, the vehicle body or box; I, the steering-gear, and J brake mechanism.

The front and intermediate axles are provided with universal joints K, affording dirigible spindles K' for the front and intermediate wheels. Each spindle is equipped with a wheel-frame L, having vertical standards L' and horizontal members L'' L''. Each member of each wheel-frame comprises two members separated by a sufficient space to accommodate the wheel, and the two members of each standard L' are bent inwardly at their upper portions to afford a projection or bracket L''. The inner member of each standard L' is provided at its base with an inward 45 projection or bracket L''. The inner ends of 50

the brackets L'' L''' are connected by a vertical stud or guide L'', which projects upwardly beyond the bracket L'' and through a bushing L'', with which the body H is provided. Confined between the bushings L'' and brackets L'' are springs L'', which surround the upper portions of the studs L''. Above the bushings L'' the studs L'' are equipped with collars L'', which move in housings L''. The box H is provided with a plurality of lateral 60 projections M, having perforations or slots through which the vertical members L'' extend freely, and the box is also provided with a plurality of downward extensions M', provided with slots M'', engaging the axles at reduced portions or circumferential grooves M''. The wheel-frames may be covered with netting or any other suitable material, if desired. The front wheel-frames are equipped with inwardly-projecting U-shaped arms N, 70 and the intermediate wheel-frames are equipped with similar arms N', of greater length, however.

The steering-gear I comprises a vertical shaft a, journaled in a suitable bearing in 75 the bottom of the vehicle-body; a handle a', attached to the upper end of said shaft; a lever a'', rigidly connected with the lower end of said shaft; rods a'', connecting the extremities of the lever a'' with the inner ends 8c of the arms N', and rods a'', connecting the arms N' with the arms N.

The brake mechanism J comprises a hand-lever b, extending through a slot in the bottom of the vehicle-box and rigidly connected 85 with a shaft b', journaled in suitable bearings b'' beneath the box; arms b'' b'', rigidly connected with the shaft b'; links b'' b'', pivotally connected with the lower ends of the arms b'' b'', respectively; a cross-bar b'', firmly 90 fixed to the truss portions b'' of the reaches of the vehicle and projecting at its ends beyond said reaches; clips b'', firmly secured to the ends of the cross-bar b''; links b''', pivotally connected with the clips b'''; links b''', 95 pivotally connected with the links b''', the joints between the links b''' and b''' being connected with the rods b'' b'', respectively; drag-blocks b''', pivotally connected with the links b'''; links b''', pivotally connected with the 100

front ends of the blocks b^{13} and passing at their front ends through clips b^{15} , with which the front end of the box is equipped; springs b^{16} , connected with the front ends of the links b^{14} and bearing against the clips b^{15} , and links b^{17} , pivotally connected at their front ends with the blocks b^{13} and at their rear ends with depending brackets b^{18} , with which the rear end of the vehicle-body is equipped.

10 The manner of use and features of advantage will be readily understood from the foregoing description. Power is applied to the axle D' from any suitable motor and is communicated from the said axle to the other axles through suitable sprocket wheels and chains, as indicated. Compensating gears are employed where necessary. When the steering-handle a' is turned in either direction, the bar or lever a^2 is correspondingly turned, thereby causing the front and intermediate sets of wheels to turn correspondingly. By reason of the fact that the arms N' are longer than the arms N the front wheels are turned more than the intermediate wheels, the proper ratio being secured in designing the arms to cause the wheels to move naturally and without slipping. When it is desired to apply the brake, the upper end of the hand-lever J is drawn backwardly, thereby drawing the links $b^6 b^7$ forwardly, straightening the toggle-levers formed by the links $b^{11} b^{12}$, and depressing the blocks b^{13} into engagement with the road.

As will be readily understood, a vehicle-body supported upon three sets of wheels is subjected to much less jolting than one supported upon two sets of wheels. Thus either set of wheels may pass over an obstacle without the box being raised perceptibly. In like manner either set of wheels may pass into a depression without the box partaking of the motion. While for ordinary purposes it is sufficient to support the vehicle-body at three transverse lines, yet it may be advantageous in some instances to employ more than three sets of wheels. In any case the rear axle may be without universal joints, or universal joints may be employed thereat also. Such spindles as are dirigible should be connected to be simultaneously controlled.

The improved brake mechanism enables the vehicle to be brought to a stop quickly without injury to the wheels of the vehicle.

It will be understood that, if desired, a pole may be connected in any suitable manner with the front wheel-frames or front spindles and the shaft a and attendant hand-steering mechanism dispensed with, if desired. This would convert the vehicle into a horse-drawn vehicle, and many of the features of advantage hereinbefore explained would be retained.

Changes in details of construction within the spirit of my invention may be made.

Hence no undue limitation should be understood from the foregoing detailed description.

What I regard as new, and desire to secure by Letters Patent, is—

1. In a vehicle, the combination of a body, 70 wheels supporting said body at three or more transverse lines, and steering means for turning the front and intermediate wheels simultaneously in the same direction with relation to the vehicle-body, for the purpose set forth. 75

2. In a vehicle, the combination of a body, three or more sets of wheels, axles connecting said wheels, spring-supporting standards connected with the end portions of said axles, and springs confined between the upper portions of said standards and said box, for the purpose set forth. 80

3. In a vehicle, the combination of a body, three or more sets of wheels, axles connecting said wheels, two of said axles being provided with dirigible spindles connected by universal joints, spring-supporting standards connected with said spindles, springs thereon supporting said box, and a steering-gear connected with said spindles, whereby said spindles may be simultaneously turned with relation to the vehicle-body, for the purpose set forth. 85 90

4. In a vehicle, the combination of a body, 95 wheels, axles connecting said wheels in pairs, and having universal joints affording dirigible spindles, wheel-frames connected with said spindles having inwardly-projecting brackets, vertical studs connected with said brackets and extending through suitable 100 guides on said body, and springs confined between said projections and said body, for the purpose set forth.

5. In a vehicle, the combination of a body, 105 wheels, axles connecting said wheels in pairs, and having universal joints affording dirigible spindles, wheel-frames connected with said spindles having inwardly-projecting brackets, vertical studs connected with said brackets and extending through suitable 110 guides on said body, springs confined between said projections and said body, inwardly-projecting arms connected with said wheel-frames, and steering-gear connected with said arms. 115

6. In a vehicle the combination of a body, 120 wheels, axles connecting said wheels in pairs and provided with universal joints provided with dirigible spindles, wheel-frames connected with said spindles and supporting said body, inwardly-projecting arms connected with said wheel-frames, one set of arms being of greater length than the other set, links connecting corresponding arms, and means for moving one set of arms, for the purpose 125 set forth.

7. In a vehicle, the combination of a body, 130 wheels, axles connecting said wheels in pairs

and provided with universal joints affording
dirigible spindles, wheel-frames supported by
said spindles and each provided with two in-
wardly-projecting brackets, studs connecting
5 said brackets and projecting above the upper
bracket, springs supported on the upper
brackets and supporting the vehicle-body,
and means for controlling the movements of
said spindles, for the purpose set forth.

EARNEST LOHSAND.

In presence of—

L. HEISLAR,
ALBERT D. BACCI.
